(57) **CLAIM**

We claim the ornamental design for a portable electronics tray, as shown and described.

DESCRIPTION

FIG. 1 is a top, perspective view of a portable electronics tray showing a first embodiment of our design;
FIG. 2 is a bottom, perspective view thereof;
FIG. 3 is a back view thereof;
FIG. 4 is a front view thereof;
FIG. 5 is a top view thereof;
FIG. 6 is a bottom view thereof;
FIG. 7 is a right side view thereof;
FIG. 8 is a left side view thereof;
FIG. 9 is a top, perspective view of a portable electronics tray showing a second embodiment of our design;
FIG. 10 is a bottom, perspective view thereof;
FIG. 11 is a right side view thereof;
FIG. 12 is a left side view thereof;
FIG. 13 is a top view thereof;
FIG. 14 is a bottom view thereof;
FIG. 15 is a front view thereof; and,
FIG. 16 is a back view thereof.
